His Attorney.

UNITED STATES PATENT OFFICE.

HARRY L. HUSSMANN, OF ST. LOUIS, MISSOURI, ASSIGNOR TO HUSSMANN REFRIGERATOR & SUPPLY COMPANY, OF ST. LOUIS, MISSOURI, A CORPORATION OF MISSOURI.

SHOWCASE REFRIGERATOR.

Application filed April 21, 1921, Serial No. 463,250. Renewed July 16, 1923.

To all whom it may concern:

Be it known that I, HARRY L. HUSSMANN, a citizen of the United States, and residing at St. Louis, Missouri, have invented the new and useful Improvement in Showcase Refrigerators, of which the following is a specification.

This invention relates to a refrigerator, and more particularly to show case refrigerators, such as disclosed in Patent No. 1,225,682, patented May 8, 1917, and which is provided with a container for the refrigerant or freezing mixture, mounted usually at one end, and which communicates with a cooling chamber or show case, provision being made for the circulation of air about the refrigerant container and through the cooling chamber or show case.

One of the objects of this invention is to provide simple and convenient means for removing the refrigerant container.

Another object is to provide such means for removing the container through a side door, and in such a way as not to interfere with the air circulation system.

Another object of this invention is to provide a pan mounted and arranged for catching the drip from the container when the latter is moved out of the refrigerator.

Further objects will appear from the detail description taken in connection with the accompanying drawing, in which:

Figure 1 is a rear elevation showing a show case refrigerator embodying this invention;

Figure 2 is a section on line 2—2, Figure 1;

Figure 3 is a detail showing the method of securing the pan;

Figure 4 is a detail showing the construction of the hinge for the pan;

Figure 5 is a view in elevation of the structure of Figure 4; and

Figure 6 is a section on line 6—6, Figure 5.

Referring to the accompanying drawing, the refrigerator comprises the usual cooling chamber or show case 1 and a chamber or compartment 2 for housing the refrigerant container, from which the drippings fall. A side door 3 is provided for the removal of the container. The door 3, in this case, swings on a vertical axis on hinges 4. Within the chamber or compartment 2 is a refrigerant container 5 which may be provided

with air passages 6 to permit circulation of the air therethrough as shown in said patent.

The container 5 may be provided with rollers 7 arranged to run on a pair of rails 8 mounted on supports 9 on the interior of the chamber 2. The rails 8 are arranged transversely of the chamber 2 and in such a way that the container 5 may be moved theralong and out of the door 3. The rails 8 are preferably constructed of angle iron which may be equipped with a sheet iron trough 10 as shown in Figure 6 so as to prevent the rollers 7 from leaving the rails.

Hinged at 11 to the ends of the rails 8 are a pair of extension rails 12 having permanently attached thereto and adapted to support a pan 13 so as to be movable therewith. The hinges 11 are located just with in the door 3 and the rails 12 and the pan 13 are arranged so that when the door 3 is open, the pan may be let down upon the hinges 11 until the rails 12 rest upon the door sill 14 and the pan will be supported in a horizontal position extending through the door way, as shown in dotted lines in Figure 2. When the pan is lowered in this position, the container 5 may be run out upon the rails 12 and over the pan 13 to the dotted line position Figure 2 from which position it may be easily removed from the refrigerator. The pan 13 is equipped with an extension 15 extending to within the refrigerator and sloping downwardly for drainage. This is provided so that drippings from the container 5 when run out on the rails 12 will accumulate in the pan 13 and drain to the inside of the refrigerator compartment by way of the extension 15 overlapping the sill 14. In returning the container 5, it may be replaced upon the rails 12 and run into the chamber 2. After this is done, the rails and pan 13 are raised on the hinges 11 to the full line position in Figure 2, with the pan in the door-way and against the container. It may be latched in this position by means of a latch 16 engaging a depression 17 in the top of the chamber 2.

It will be seen that the container may be removed from the refrigerator by means of this device in a very simple and efficient manner. The door 3 being placed at the side may be opened without interference with the circulating air currents. When the pan 13 is lowered, the container may quick-

ly be run out to a position convenient for handling and can be as easily and quickly returned. When not in use, the pan 13 folds into a small space where it is out of the way.

It is obvious that various changes may be made in details of construction without departing from the spirit of this invention; it is, therefore, to be understood that this 10 invention is not to be limited to the specific details shown and described.

Having thus described the invention, what is claimed is:

1. In a show-case refrigerator, having a 15 compartment, a refrigerant container therein and a door-way therefor, and means for guiding said container for movement into and out of said compartment, including a pan mounted for movement into and out of 20 said doorway.

2. In a show-case refrigerator, having a compartment, a refrigerant container therein and a door-way therefor, means hinged at the bottom of and for movement into and 25 out of said doorway, adapted for guiding said container for movement into and out of said compartment, and a pan on said guiding means and movable therewith into and out of 30 said door-way.

3. In a show-case refrigerator, having a compartment, a refrigerant container therein and a door-way therefor provided with a sill, means mounted for movement out of 35 said compartment and on said sill and into said compartment and against said container; adapted for guiding said container for movement into and out of said compartment, and a drip pan on said guiding means and movable therewith into and out of 40 said door-way.

4. In a show-case refrigerator, having a compartment, a refrigerant container therein and a doorway therefor, rails for guiding 45 said container for movement into and

out of said compartment, and a pan permanently attached to and supported by said rails and movable therewith.

5. In a show-case refrigerator, having a compartment, a refrigerant container therein and a doorway therefor provided with a 50 sill, rails supported by said sill for guiding said container for movement into and out of said compartment, and a drip pan permanently attached to and supported by said rails and movable therewith. 55

6. In a show-case refrigerator having a compartment, a dripping refrigerant container therein and a door-way therefor, means for guiding said container for movement into and out of said compartment, and a drip-receiving pan mounted for movement beneath said container when said container is out of said compartment and adapted to catch the drip therefrom when so positioned, said pan being mounted for movement into 60 said door-way and within said compartment when said container is positioned therein.

7. In a show-case refrigerator having a compartment, a dripping refrigerant container therein and a door-way therefor, 70 means for guiding said container for movement into and out of said compartment, and a drip-receiving pan mounted for movement beneath said container when out of said compartment and for movement against 75 said container when in said compartment.

8. In a show-case refrigerator having a compartment, a dripping refrigerant container therein and a door-way therefor, 80 means for guiding said container for movement into and out of said compartment, and a drip-receiving pan mounted for movement beneath said container when out of said compartment and constructed to drain into said compartment. 85

In testimony whereof I affix my signature this 11th day of April, 1921.

HARRY L. HUSSMANN.
